UNITED STATES PATENT OFFICE.

LESLIE W. MORTON, OF CANTON, ILLINOIS.

RAIL-DRILL DRIVE AND FRAME THEREFOR.

1,074,557.

Specification of Letters Patent. Patented Sept. 30, 1913.

Original application filed June 26, 1911, Serial No. 635,366. Divided and this application filed December 20, 1911. Serial No. 666,943.

To all whom it may concern:

Be it known that I, LESLIE W. MORTON, a citizen of the United States, residing at Canton, in the county of Fulton and State of Illinois, have invented certain new and useful Improvements in Rail-Drill Drives and Frames Therefor; and I do hereby declare the following to be a full, clear, and exact description of the invention, such as 10 will enable others skilled in the art to which it appertains to make and use the same.

This invention relates to drilling machines, and it particularly relates to an improved mechanism for operating rail drills, 15 and the subject matter thereof originally formed a part of my application, Serial #635,366, and is a division thereof.

An object of this invention is to provide an improved jointed rail drill carrying and 20 operating mechanism which is capable of being adjusted in various positions, whereby the drilling tool may be shifted without moving the support which carries the drilling mechanism.

Another object of the invention is to provide a mechanism of this character which is strong, durable, simple of construction and operation, and thoroughly 25 efficient.

Other objects and advantages may be recited hereinafter and in the claims.

In the accompanying drawings, which supplement this specification, Figure 1 is a side elevation view of the mechanism. Fig. 35 2 is a detail view of the lower end of one of the depending frame members. Fig. 3 is a vertical sectional view through one of the bearing members and its adjuncts. Fig. 4 is a vertical sectional view through other 40 of the bearing members and through the upper portion of the depending frame. Fig. 5 is a sectional view on the line 5—5 of Fig. 4. Fig. 6 is a sectional view on the line 6—6 of Fig. 4, and Fig. 7 is an elevation 45 view, in detail, of an improved form of combined bearing and journal, which also forms a connection for certain other elements of the device.

Referring to the drawings, in which similar reference characters correspond with

similar parts throughout the several views: the reference character 1 designates the support, which consists of a substantially horizontal base having vertical arms or standards extending upward, in parallel spaced 55 relation to each other and carrying collars or journal bearings (not shown), in which a driver shaft 2 is mounted for rotation, said driver shaft being connected with any proper source of motive power (not shown). 60 A beveled gear wheel 3 is secured on the shaft 2, between the vertical sides of an inverted-U-shaped bearing member 4 which is pivotally mounted on the shaft 2, between the standards 1. The upper portion 5 of 65 the U-shaped member 4 is substantially horizontal, when in normal position, and is centrally apertured for the reception of a combined journal and bearing element 9, of similar construction as the element 25 shown 70 in Figs. 4 and 7; this element 9 being provided with a head, which is seated under the bearing element 5, and with a journal element 9' which extends through the bearing element 5, being screwed into an element 75 6, of a journal bearing 8 as shown in Fig. 3. Through the central aperture of the element 9, extends a shaft 10', which carries a gear wheel 10 and a gear wheel 11 on its opposite ends; the gear wheel 10 being in mesh 80 with the gear wheel 3, and the gear wheel 11 being in mesh with a gear wheel 12 which carries a shaft 13, the latter being journaled in the journal bearing 8 which is formed integrally with the vertical member 85 7 and with the horizontal member 6.

An element of similar construction to that which is shown in Fig. 3, consists of a journal bearing 14, and an L-shaped supporting and connecting element, the vertical and horizontal portions of which are designated 90 15 and 16, respectively. The shaft 13 extends through and has its bearing in the elements 14 and 15, while the member 25 is secured, by means of its screw threads, to 95 the element 16, thereby forming a pivotal connection or journal, on which is seated an inverted-U-shaped hanger or bearing member, the latter consisting of depending arms 100 connected by a substantially horizontal 100

plate 17; said plate being seated upon the head or flange element of the member 25 and supported thereby. A short vertical shaft (not shown), is journaled in the member 25, and carries a bevel gear wheel 23 and a bevel gear wheel 24, the latter meshing with a bevel gear wheel 26 which is secured on the end of the shaft 13 opposite to the end on which the gear 12 is seated.

10 The lower end portions of the elements 18 are apertured for the reception of a shaft 19, said shaft having its ends mounted in the upper portion of a frame which consists of a pair of parallel depending bars 21, and connecting members or struts 35 and 37, these latter members also constituting bearings, in which is journaled a shaft 36, having bevel gear wheels 38 and 39 secured on its respective ends. A bevel gear wheel 22 is mounted on the shaft 19 and adapted to rotate thereon, said bevel gear being in mesh with the bevel gears 23 and 38. The strut or frame member 37 is secured to the members 21 by means of bolts 40, and it is obvious that the strut 35 is susceptible of being similarly connected or secured; however, it is clearly obvious that the end portions 20, of the frame may be secured in fixed relation with each other by means of the shaft 19, in which case, the wheel 22 would not be fixed on the shaft 19, but would be free to rotate thereon; whereas, if the members 21 are held in fixed position by the member 35, the wheel 22 may be secured on the shaft 19 and rotate therewith. It is also obvious, that the gear wheel 3 may be rotated by any proper means, independently of the shaft 2. The elements 20 and 21 of the frame are connected by or formed integrally with the diagonal or outwardly flared portions 34. The lower ends of the depending bars 21 are formed with enlarged cylindrical portions 41, which are apertured at 42, to form a bearing in which is journaled a gear wheel 39' meshing with the gear wheel 39, for driving the drill shaft 39^a, which carries the drill 39^b.

50 In operation, the supporting bracket 1 is stationed and secured upon a car, truck or other proper support (not shown), above the level of the rails which are to be drilled, said support being of such height that the center of the portions 41 are on or slightly below the level of the portion of the rail which is to be drilled, when the frame 21 is in vertical position. It will be seen that, by swinging the frame 21 on its pivotal point at 19, the center at 41 will be moved upward, as well as in a lateral direction, so that the holes may be drilled at any desired point in the rails. It will also be seen that by swinging the members 7, 13, 14, 15 and 21 around the axis of the wheels 10 and 11, the direction of the drill may be

changed so as to point in the opposite direction, and it may then be employed for drilling holes in the opposite rail.

Inclosing the shaft 13 is a tube or casing 27, having its ends fitted in the enlarged openings 28, in the sleeves 8 and 14. This tube is retained in fixed position relative to the sleeve 8, by any proper means, and unites therewith to form a combined bearing and journal member, the member 14 being pivotally mounted or journaled on the sleeve 27 and being retained thereon by means of a clamp 29, said clamp being formed with ears 30 which are apertured for the reception of a bolt 31 having a nut 32 fitted thereon and adapted to coact therewith for drawing the ears 30 into proximity, and causing the member 29 to fit tightly and securely around the sleeve 27. The clamp 29 is provided with a retainer element 33 having an arcuate or segmental groove therein, and the groove of the clamp fits snugly over a shoulder or bead 14' of the sleeve 14, and this retainer element prevents longitudinal movement of the tube 27 relative to the sleeves 8 and 14.

I do not limit my invention to the exact details of construction, combination and arrangement of parts as herewith illustrated and described, but my invention may only be limited by a reasonable interpretation of the claims.

What I claim is:

1. A drive and frame comprising a plurality of shafts carrying gears and means for connecting the shafts and holding the gears in mesh with one another, a sleeve for one of the shafts, parallel side pieces for supporting one of said shafts, means for connecting the sleeve and the parallel side pieces for supporting the shafts carried by the sleeve and the parallel side pieces in angularly adjusted position in relation to each other, braces for connecting the side pieces and receiving the shaft and holding the latter in position between the parallel side pieces, the lower ends of said side pieces being adapted for engagement with a drill shaft to support the latter, the shaft between the parallel side pieces having a gear upon its lower end for mesh with a gear carried by the drill shaft to rotate the latter, and means for supporting one end of the drive and frame upon a platform.

2. In a drill driving mechanism, a supporting bracket, a rotary driver element carried thereby on a horizontal axis and a transmission mechanism mounted for angular adjustment around the axis of the driver element and including a plurality of intermeshing gears, a normally horizontal shaft which is mounted for swinging movement in a horizontal plane around a point above the driver member, a depending frame, means connecting the frame with the hori-

zontal shaft and being rotatable relative thereto, a normally vertical shaft carried by the frame, said frame providing means adapted for supporting a drill, and a gear 5 carried by said vertical shaft and adapted for actuating the drill.

In testimony whereof I have signed my

name to this specification in the presence of two subscribing witnesses.

LESLIE W. MORTON.
